(57) **CLAIM**

The ornamental design for a keyboard cover, as shown and described.

DESCRIPTION

FIG. 1 is a front perspective view of the keyboard cover showing our design;

FIG. 2 is a front view thereof;

FIG. 3 is a left side view thereof;

FIG. 4 is a right side view thereof;

FIG. 5 is a rear view thereof; and

FIG. 6 is an enlarged view of a key in FIG. 1; and,

FIG. 7 is an enlarged view of the key in FIGS. 1 and 6.

Portions of the keyboard cover shown in broken lines are not part of the claimed design.

1 Claim, 5 Drawing Sheets
